W. J. Duvall, ATTORNEY.

UNITED STATES PATENT OFFICE.

HARRY W. BOLENS, OF PORT WASHINGTON, WISCONSIN.

CHAIR-IRON.

1,330,427.

Specification of Letters Patent. Patented Feb. 10, 1920.

Application filed January 2, 1919. Serial No. 269,305.

To all whom it may concern:

Be it known that I, HARRY W. BOLENS, a citizen of the United States, residing at Port Washington, in the county of Ozaukee 5 and State of Wisconsin, have invented new and useful Improvements in Chair-Irons, of which the following is a specification.

My invention relates to improvements in chair-irons, and has special reference to that 10 portion thereof commonly termed the "hub."

In the conventional form of hub it is usual to employ a central sleeve and permanently connect to the upper end of the same a top-plate. About this sleeve is located at equidistant points leg-receiving sockets either cast integral with the sleeve and top-plate, or, where formed of sheet-metal, secured to one or the other or both of such elements. In either instance, the 15 practice is to permanently secure the top-plate in position, so that in assembling the legs within the hub to form the chair-base, the hub is necessarily reversed or turned bottom-side up so that the top-plate is then 20 at the bottom. After this, the inner ends 25 of the chair-legs, which have been previously shaped to fit, are driven forcibly downward into the leg-sockets, subsequent to which a bottom-plate is applied to the 30 lower end of the hub and secured to the lower or bottom edges of the legs by means 35 of wood-screws. In order that the legs may have a snug or driving-fit within the sockets, it is customary to converge the walls 40 thereof toward their upper ends, and so also, are said walls of the sockets converged 45 laterally, the inner ends of the legs being formed with corresponding dove-tailed tenons. The driving-fit of the legs within the leg-sockets is depended upon to prevent 50 looseness, and the bottom ring or plate is depended upon to prevent the legs from spreading and pulling from the sockets 55 when the load is applied as when the chair is in use.

It will be appreciated, therefore, that according to the present practice of manufacturing revolving and tilting chairs, the legs of the chair-base are clamped by the leg- 50 sockets more tightly at their upper inner corners than they are at their lower inner corners, notwithstanding the obvious fact that when the load is applied at the center 55 of the chair-base, the tendency is to spread the legs at their lower ends and force them from their sockets and at the same time

force the upper corners of the legs inward. Indeed, to prevent this tendency to spread, is the function of the lower ring or bottom-plate.

The principal objects of my invention are to overcome this obvious defect in construction, which I purpose doing by converging the side-walls of the sockets toward their lower ends instead of their upper ends, such 65 necessarily requiring that the top-plate be made independent of the remainder of the hub and secured in position after instead of before the application of the legs to the hub; and furthermore, to lighten as well as 70 cheapen the hub as a whole by rendering unnecessary the employment of the usual central sleeve, which I accomplish by adapting the inner walls of the sockets themselves to perform the function of the hub. 75

Other objects and advantages of the invention will hereinafter appear, and the novel features thereof will be particularly pointed out in the appended claims.

Referring to the drawing:

Figure 1 is a transverse sectional view, taken on the line 1—1 of Fig. 2, of a chair-iron hub embodying my invention, the outer ends of the legs being broken away; and

Fig. 2 is a side elevation of the same. 85

Similar numerals of reference indicate similar parts in both figures of the drawing.

The hub consists of a series of four annularly arranged sockets 1, a top-plate 2, and a bottom-plate 3, the usually present central sleeve being entirely omitted. 90

These sockets may be, and preferably are, simply short separate independent sections cut from a length of channel-iron formed of sheet-metal of proper gage, said sections 95 being arranged in position and preferably in contact and secured together so that their inner or back-walls combine to form a central tubular space 4. This space may, if desired, be of any shape in cross-section, 100 but is preferably substantially cylindrical so as to simulate the usually employed sleeve for which it forms a substitution. The cylindrical form may be secured by curving the rear or back-wall 5, of each socket upon 105 the arc of a common circle. The opposite side-walls 6 of each socket-section are preferably converged toward their lower ends as well as toward their outer edges, so that the socket viewed either in cross-section or elevation is wedge-shaped. Converging the walls of the socket toward their lower ends,

it will be observed, is directly contrary to the conventional practice, it being usual, as heretofore stated, to converge these walls toward their upper ends.

5 The socket-sections may be conveniently cut from blanks or lengths of channel-iron of sheet-metal of the desired shape in cross-section, the only essential being that such blanks comprise opposite side and an intermediate connecting wall. And, as a matter of fact, the sections could be produced from blanks L-shaped in cross-section, in which instance, of course it would require two sections for each socket. The sections when 10 assembled may be permanently connected in any desired manner, but preferably by spot-welding at their meeting corners. Although other means may be used for connecting the upper ends of the sockets and top-plate, I 15 prefer to provide the former with end-tenons 7, and the plate with corresponding mortises 8, upwardly through which the tenons may pass and above which they may be headed by a few taps of a hammer after 20 the chair-legs 9, have been driven downwardly into position within the sockets.

The inner ends of the chair-legs, following the usual practice, are shaped to form dove-tailed tenons 10, of a uniform 25 width or thickness and which correspond in cross-section to the shape of the sockets. In advance of the tenoned ends of the legs 30 vertical shoulders 11, are formed and these abut against the front edges of the side-walls of the sockets.

In assembling the legs in the hub thus formed, the legs are driven downwardly into the sockets, and the latter being slightly narrower at their lower ends than at their 35 upper ends whereas the tenons of the legs are uniform in width, a driving-fit results, as heretofore, except that the sockets clamp the legs more tightly at the lower inner corners of the latter than at their upper inner corners in direct contravention to the 40 conventional construction and method. This, according to my conception, is as it should be, because, as before indicated, the legs are clamped tightest within the sockets at 45 those points where the greatest tendency is to spread by reason of the load. After the legs have been positioned as described, the top and bottom-plates are applied, the latter as usual (by means of screws inserted 50 upwardly through the plate and into the undersides of the legs) and the former by having the tenons 7 upset by a few blows of a hammer. Of course, any means may be 55 employed for securing the top-plate in position, and I do not limit my invention to the inclusion of the means shown, such merely being a suggestion of one simple 60 means to an end. So also, with regard to the bottom-plate, other means may be employed for securing it in position, or, if 65

preferred, it may be omitted altogether, as the snug fit of the legs now at the lower instead of the upper inner corners of the legs within the sockets, may, in practice, render its presence entirely unnecessary. 70

The tubular space 4, formed by the inner curved walls of the sockets, will be found to serve the functions of the usual central sleeve, so that the cost as well as the weight of the latter is avoided. Into this space 75 may be inserted any of the usual elements employed for giving vertical adjustment to the chair-seat as well as permitting of the chair being revolved.

Having described my invention, what I 80 claim, is:

1. The combination with a chair-hub having annularly arranged dove-tailed sheet-metal sockets connected together, each socket comprising opposite side-walls converging toward their lower ends, of chair-legs the inner ends of which are provided with tenons of uniform width and having a driving fit downwardly into said sockets between the downwardly converging walls 90 thereof and upper and lower plates for the sockets.

2. A chair-iron, comprising, a series of annularly arranged leg-receiving sockets, each of said sockets comprising opposite outwardly disposed side-walls converging toward their lower ends, a series of legs the inner ends of which have a driving fit downwardly into said sockets and between said downwardly-converging walls of the sockets, 100 whereby said legs are clamped by said side-walls at their lower sides or bottoms to a greater degree than at points thereabove, a top-plate for the inner ends of the legs and upper ends of the sockets, and means for 105 securing said top-plate in position.

3. A chair-iron, comprising, a series of annularly arranged leg-receiving sockets, each of said sockets comprising opposite outwardly disposed side-walls converging 110 toward their outer edges and lower ends, a series of legs having their inner ends tenoned, which tenons are of substantially uniform width and having a driving fit downwardly into said sockets, whereby said legs 115 are clamped by said side-walls at their lower sides or bottoms to a greater degree than at points thereabove, a top-plate for the inner ends of the legs and upper ends of the sockets, and tenons provided on the 120 upper ends of the sockets and engaging mortises correspondingly formed in said top-plate.

In testimony whereof I have signed my name to this specification in the presence of 125 two subscribing witnesses.

HARRY W. BOLENS.
